UNITED STATES PATENT OFFICE.

HARRY E. TOWNSEND, OF BROOKLYN, NEW YORK.

SEALING MACHINE.

Application filed August 26, 1919. Serial No. 320,008.

This invention relates to sealing-machines, and has particular reference to a machine having a plurality of continuously rotating sealing mechanisms adapted for sealing bottles, jars, tumblers, etc., in a vacuum.

One of the objects of my invention is to provide a machine of this character which is simple in construction, and rapid and efficient in operation.

10 Another object of my invention is to provide a continuously operating vacuum sealing machine with means actuated by air pressure for automatically opening and closing the vacuum chambers.

15 Another object of this invention is to provide a machine of this type having a plurality of vertically reciprocating vacuum chambers and a sealing device in each chamber, with means whereby both a chamber and 20 a sealing device will be actuated by air pressure acting on a single actuating device.

Another object is to provide a machine of 25 this type in which a single valve will control the opening and closing of the vacuum chambers, the exhaustion of the air therefrom, and the operation of the sealing devices.

Another object is to provide an exhaust chamber within the frame of the machine and a pump actuated by the driving mechanism of the machine for exhausting the air therefrom; and still other objects will appear in the following description and claims.

I attain these objects by the mechanism illustrated in the accompanying drawings, in 30 which—

Figure 1 is a front elevation of the machine; Fig. 2, a vertical sectional view on the lines 2 2, Figs. 3 and 4; Fig. 3, a sectional plan view on the line 3 3, Fig. 2; Fig. 40 4, a sectional plan view of the upper part of the machine on the line 4 4, Fig. 2; Fig. 5, a bottom plan view of the valve controlling the air and exhaust connections; Fig. 6, a vertical sectional view of this valve on the line 6 6, Fig. 5, showing also the actuating cylinders and exhaust connections leading thereto diagrammatically arranged with reference to this valve; Fig. 7, a development 45 of the conical surface of the valve shown in Figs. 5 and 6, in which, for the purpose of avoiding curved lines, the circumferences of the top and bottom of the valve are assumed to be equal; Fig. 8, a sectional detail of the feeder and discharging wheels; and Fig. 9, 50 a sectional detail of the valves controlling

the exhaustion of air from the exhaust chamber by the pump.

Similar numerals refer to similar parts throughout the several views.

The bed plate 10 and the cylindrical column 11 constitute the frame of the machine. The column is provided with a shoulder 12, on which rests the ball bearing 13, supporting the carrier 14, revolubly mounted on the said column. The worm wheel 16, secured 60 to the lower end of the carrier by the feather 15, and engaging with the worm 17, secured to the shaft 18, having bearings in the brackets 92 and 93, constitute the drive for the carrier by which it is given a continuous 65 rotary motion.

The carrier is provided with a flanged portion 19 which serves as the package table of the machine. To this upper part of the carrier are bolted the cylinders 20, provided with covers 21, and in which work the pistons 22, provided with packing rings 23. Attached at their upper ends to the pistons are the tubes 24, having bearings in the extensions 25 of the cylinders, and terminating at their lower ends with the flanges 26. Slidably mounted on the lower ends of the tubes are the vacuum chambers 27, provided with glands 28 and packing 29, to make airtight joints between the chambers and 80 tubes. The chambers are adapted to seat on the rubber gaskets 30, set into the table 19, to form an enclosed space around a package from which the air may be exhausted to obtain a vacuum in the package. 85

The interiors of the extensions 25 of the cylinders are cored out to provide recesses 31 around the tubes 24, which are in communication with the exhaust and the atmosphere alternately by means of the pipes 32. Air-tight joints are made between the tubes and the lower ends of the extensions by the glands 32^a and the packing 32^b. The upper ends of the cylinders are similarly in communication with the exhaust and the atmosphere alternately by means of the pipes 33. 95

Into the lower ends of the tubes 24 are screwed the stems of the sealing plates 34, faced on their under sides with the rubber pads 35. The machine is shown in the present instance adapted for sealing the closure shown and described in my co-pending application Serial No. 274,071, to seal which it is only necessary to push the closure down into the mouth of the container to be sealed. 100 105 110

It will be obvious, however, that the machine could be used for sealing various other styles of closures.

The tubes 24 are provided with long slots 36 by means of which, when the pistons 22 are in the high position, the spaces below the pistons are in communication with the recesses 31 through the interior of the tubes. The upper ends of the tubes are closed by 10 the plugs 37 to prevent communication through the tubes between the upper and lower sides of the piston. The lower ends of the tubes are provided with drilled holes 38, which are normally closed by being within 15 the bearings of the vacuum chambers on the tubes, so as to prevent air being drawn into the tubes through the chambers before the chambers are closed.

It will be readily understood from the foregoing that if the air is exhausted from a recess 31, and air under atmospheric pressure admitted to a cylinder above the piston, the piston and the tube 24 will move down until the vacuum chamber is seated on the 20 package table, thus enclosing the package to be sealed. As the tube 24 continues to move down, sliding in its bearing in the chamber, the hole 38 in the lower end of the tube will be uncovered and the air in the chamber and consequently in the package will be exhausted. The continued downward motion of the tube causes the sealing plate 34 to push the closure down into the mouth of the container, thereby sealing the container 25 and arresting the downward motion of the tube. In order to allow sufficient time for the air in the chamber to be fully exhausted before the package is sealed, the slot 36 in the tube is so positioned that after the hole 30 38 is uncovered and before the package is sealed, the slot moves out of communication with the cylinder 20, after which the remainder of air below the piston is exhausted through the small hole 38^A, delaying the 35 descent of the piston and, consequently, the sealing of the package until the air has been fully exhausted therefrom.

If, now, the conditions as to exhaust and atmospheric pressure be reversed in a manner to be presently described, exhausting the air above the piston and admitting air under atmospheric pressure below the piston, the piston and tube will move upward to the high position, and during the upward movement the gland 28 will be brought against the gland 32^A in the extension 25, causing the chamber to be pushed down on the tube until the gasket 39 is clamped between the chamber and the flange 26, thereby making an 40 airtight joint between the interior of the chamber and tube 24.

As several of the sealing mechanisms are in operation at the same time, in some of which the air is being exhausted from the 45 cylinder 20, while in others it is being ex-

hausted from the vacuum chambers, it is not only necessary to provide adequate exhausting means but it is important that the exhaust be constantly uniform to insure the same degree of vacuum in every package. It 70 is usual under similar conditions to install a tank of considerable cubical capacity between the sealing machine and pump, into which the air exhausted from the machine is discharged, and from which it is exhausted 75 by the pump. The tank acts as a reservoir, so to speak, for the vacuum, in which the degree of vacuum is but little affected by the successive discharges of air from the sealing machine. This arrangement results 80 in the desired equalization of the exhaust, but involves considerable expense and labor in the installation of the machine, and the combination of pump, tank and sealing machine occupy much valuable space in the 85 packing plant.

In the present invention, I have combined the machine, pump and tank or exhaust chamber in a single unitary structure, thus effecting a considerable saving in the first 90 cost of the combination, in the cost of installation, and in the space occupied. I accomplish this by utilizing the column on which the carrier rotates as an exhaust chamber and mounting an exhaust pump above 95 the column in communication with the chamber, and connecting the pump to the driving mechanism of the machine, although it will be understood that the pump can be omitted in those cases where vacuum lines are a part 100 of the factory equipment, in which event the machine is connected directly to the said vacuum lines in a manner well understood in shop practice.

Referring to these features in detail the 105 column 11 is provided with a partition 40, serving as the bottom of the exhaust chamber, and a head 41 into which is screwed the stem of the flanged casting 42, to which is bolted the pump cylinder 43, provided with 110 the cover 44. Working within the cylinder is the piston 45, provided with packing rings 46. Screwed into the piston or otherwise having its upper end secured thereto is the tube 47, passing down through the exhaust 115 chamber and connected at its lower end with the driving mechanism of the machine by which the piston is reciprocated. The drilled holes 48 in the tube afford communication between the space above the piston and the 120 exhaust chamber, while the tube 49, set in the rubber ferrules 50 and 51, in the head of the column, and the flanged casting 42 respectively, affords communication between the exhaust chamber and the space below the 125 piston. When the piston is on the down stroke air enters the tube 47, through the holes 48, lifts the valve 52, and enters the cylinder 43 above the piston. This valve is 130 preferably made of aluminum so as to be as

light as possible and, therefore, to obstruct the passage of air as little as possible. A similar valve seated in the upper end of the tube 49 prevents the air under the piston 5 from passing through the tube 49 into the exhaust chamber. These valves, when seated on the upper ends of the tubes in which they are located, hermetically close the tubes by reason of their being provided with rubber gaskets 53, held in place by the washers 54, as best shown in Fig. 9. As the piston descends the air under it is compressed and forced out of the cylinder through the hole 55, in the bottom of the cylinder. This hole 10 is closed during the upward stroke of the piston by the valve 56, faced with a rubber pad 57, and held in place by the bracket 58. The valve is held lightly against the bottom of the cylinder against the force of gravity 15 by the spring 59.

When the piston is on the upward stroke the tube 47 is closed by the valve in its upper end, thus preventing air above the piston from passing through the tube 47 20 into the exhaust chamber, while air from the exhaust chamber passing up through the tube 49 lifts the valve in the top of the tube and enters the cylinder below the piston. The air above the piston is expelled from the cylinder through the hole 60, which is closed during the downward stroke of the piston by a valve similar to the one attached to the bottom of the cylinder, 25 already described, except that it is not provided with the spring 59, the force of gravity being sufficient to return the valve to the closing position after each discharge of air through the hole 60.

To the top of the carrier 14 is bolted the 30 casting 61, the centre of which is bored out to receive the tapered valve 62. The stem of the casting 42 passes through the valve but is a loose fit therein so as not to prevent the valve being correctly seated in the casting 61. The valve is prevented from rotating 35 with the casting 61 by reason of the tube 49 passing through it, this tube having both ends set in stationary members. Airtight joints are made between the tube and the 40 valve by the rubber ferrules 63.

The valve 62 is provided with an elongated horizontal exhaust port 64, near its lower edge, and another elongated horizontal exhaust port 65, near its upper edge. It is 45 also provided with an air port 66 above and parallel to the exhaust port 64, and another air port 67 below and parallel to the exhaust port 65. The port 66 communicates with an air chamber in the upper part of the valve, formed by the horizontal partition 68 and the vertical partitions 69 and 70. This chamber is in communication with the atmosphere through the hole 71 in the top 50 wall of the valve. The port 67 communicates with another air chamber in the lower

part of the valve, formed by the horizontal partition 68 and the vertical partitions 70 and 72. This chamber communicates with the atmosphere through the holes 73 and 74 in the bottom wall of the valve. The 55 port 64 communicates with an exhaust chamber in the lower part of the valve, formed by the horizontal partition 68 and the vertical partitions 70 and 72. The port 65 communicates with an exhaust chamber in the upper part of the valve, formed by the horizontal partition 68 and the vertical partitions 69 and 70. This chamber is in communication with the exhaust chamber in the column through the drilled holes 75, in the tube 49, and in communication with the exhaust chamber in the lower part of the valve through the cored hole 76, in the horizontal partition 68. Making the valve in this manner, with air ports communicating with air 60 chambers inside the valve instead of recessing its periphery to provide communication with the atmosphere between the valve and its seat, affords the advantage of equalizing the wear on all parts of the valve, thereby 65 preventing leakage between the valve and its seat.

The pipes 32, leading from the extensions of the lower ends of the cylinders 20, pass through the flange of the casting 61 at such a level as to be in line with the lower ports in the valve above described, and the pipes 33, leading from the upper ends of the cylinders 20, pass through this flange at such a level as to be in line with the upper ports 70 of the valve.

It will be obvious from the foregoing that, as the carrier revolves around the stationary valve, whenever the lower pipe of any pair is in communication with the lower exhaust port, the corresponding upper pipe will be in communication with the upper air port, whereby the air will be exhausted from below the piston 22, and the upper side of the piston subjected to atmospheric pressure; 75 and that the continued rotary motion of the carrier will bring the lower pipe into communication with the lower air port and the upper pipe into communication with the upper exhaust pipe, whereby the air will be 80 exhausted from above the piston and the under side of the piston subjected to atmospheric pressure. This alternation of exhaust and air pressure on opposite sides of the piston causes the piston, the vacuum 85 chamber and the sealing plate to be reciprocated in the manner already described.

To the bed plate 10 are bolted brackets 77 and 78, in which revolves the crank shaft 79 to the outer end of which is secured the pulley 80, by which the machine is driven. Also bolted to the bed plate is a bracket 81, providing bearings for the shaft 82, on which works the bell crank 83. To the vertical arm of this bell crank is connected 90

one end of the link 84, the other end of which is connected by the cap 85 to the crank formed in the shaft 79, by means of which the bell crank is given a rocking motion. 5 To the end of the horizontal arm of the bell crank is connected the lower end of the link 86, the upper end of which is connected to the eye bolt 87, screwed into the lower end of the tube 47 by which the piston 45 is 10 actuated. The tube 47 has a bearing in the bottom of the exhaust chamber, which is provided with a gland 88 and packing 89, to make an air-tight joint between the tube and the bottom of the exhaust chamber. 15 The bevel gears 90 and 91 connect the crank shaft 79 and the worm shaft 18, and it will be obvious that, by varying the proportions of these gears, any desirable ratio of speed of operation can be obtained between the 20 exhausting mechanism and the sealing mechanism. The same result can, of course, be obtained by altering the pitch of the worm 17 and worm wheel 16. Thus by the use of one or the other of these methods the machine can be adapted for sealing in a very 25 high vacuum or a low vacuum, as may be desired.

The bracket 92 provides bearings for the vertical shafts 94 and 95, to the lower ends 30 of which are secured the gears 96 and 97, engaging with the gear 98, secured to the lower part of the carrier by the feather 99. To the upper ends of these shafts are pinned the sleeves 100, as shown in Fig. 8. These 35 sleeves are used to provide additional bearing surface and, therefore, additional frictional resistance to turning for the hubs 101 and 102 of the feeder and discharging wheels clamped thereto by the screws 103. 40 The bracket 92 is provided with a lug 104, supporting the guide board 105, on which runs the conveyor belt 106, by which filled containers are brought to the machine and sealed packages removed therefrom. The 45 bracket is also provided with lugs 107, supporting the guide board 108, on which runs the return side of the belt 106. Secured to the guide board 105, by suitable screws, are the brackets 109 and 110, to which is bolted 50 the curved bar 111. Secured to this bar and extending to and over the table of the machine is the sheet iron support 112. Also secured to the guide board 105 are the brackets 113 and 114, to which is bolted the curved bar 115. Secured to this bar and extending 55 from the edge of the table of the machine to and over the conveyor belt is the sheet iron support 116.

In operation, filled containers with closures placed loosely on the top thereof are 60 brought by the belt 106 to the sealing machine. The containers may be spaced on the belt in proper sequence to arrive at the machine at just the right instant by any suitable spacing device. An arm 117 of the

feeder wheel pushes the container across the sheet iron support 112 onto the table of the machine which is revolving continuously in the direction indicated by the arrow in Fig. 3. The feeder wheel being adjustable on the shaft 94, by reason of being clamped thereto, can be set so that when the arm 117 leaves contact with the container, the container will be exactly positioned under a sealing mechanism. The rotary motion of the machine brings the pipe 32 into communication with the exhaust port 64 of the valve 62, and the pipe 33 into communication with the air port 66 of the valve, whereby the sealing mechanism is caused to operate, exhausting the air from and sealing the container in the manner already described. An arm 118 of the discharging wheel then pushes the sealed package across the sheet iron support 116 onto the conveyor belt by 85 which it is carried away from the machine.

As will be evident to those skilled in the art my invention permits various modifications without departing from the spirit thereof or the scope of the appended claims. 90

Having fully described my invention, I claim:

1. In a vacuum sealing machine, an upright column having a hollow interior constituting an exhaust-chamber, a carrier revolvably mounted on the column, a plurality of vacuum-chambers supported by the carrier, a stationary ported valve mounted above the column for controlling communication between the vacuum-chambers and the 100 exhaust-chamber, an exhaust pump above the valve, and exhaust connections from the pump to the exhaust-chamber. 95

2. In a vacuum sealing machine, an upright column having a hollow interior constituting an exhaust-chamber, a vacuum-chamber in communication with the exhaust-chamber, a piston pump mounted above the column and supported thereby, a tubular member for actuating the piston of the 110 exhaust-pump passing down through the exhaust-chamber and affording communication between the exhaust-chamber and the pump. 105

3. In a vacuum sealing machine, an exhaust-chamber, a vacuum-chamber in communication therewith, a piston pump for exhausting the air from the exhaust-chamber, a tubular member for actuating the piston of the pump passing through the exhaust-chamber and affording communication 115 between the exhaust-chamber and the pump. 120

4. In a vacuum sealing machine, an upright column having a hollow interior constituting an exhaust-chamber, a carrier adapted to revolve around the said column, 125 a plurality of vacuum-chambers supported by the carrier and in communication with the exhaust-chamber, a piston pump mounted above the column and supported thereby, exhaust connections from the pump to 130

the exhaust-chamber, and an actuating means for the pump passing down through the column and connecting at its lower end with the driving mechanism of the machine.

5. In a vacuum sealing machine, the combination with an exhaust-chamber and a vacuum-chamber in communication therewith of a piston pump actuated by the driving mechanism of the machine and having 10 exhaust connections leading from both sides of the piston to the exhaust-chamber whereby the piston is adapted to exhaust air from the exhaust-chamber while moving in either direction.

15. 6. In a machine for vacuum sealing, a container support, a vacuum-chamber adapted to engage with and be closed by the said support, a cylinder above the chamber, a piston in the cylinder, a connection between 20 the piston and the chamber whereby the chamber is reciprocated with the piston, and an exhaust connection common to the cylinder and the chamber.

7. In a machine for vacuum sealing, a container support, a vacuum chamber having an open lower end adapted to engage with the support and be closed thereby, a cylinder above the chamber, a piston in the cylinder adapted to be reciprocated by air pressure, 30 an exhaust connection intermediate the cylinder and the chamber, and a tubular member connecting the piston and the chamber and affording communication between the cylinder, the chamber and the exhaust connection.

8. In a machine for vacuum sealing, a container support, a vacuum-chamber having an open lower end adapted to engage with and be closed by the said support, a 40 cylinder above the chamber, a piston in the cylinder adapted to be reciprocated by air pressure, an exhaust connection intermediate the cylinder and the chamber, and a tubular member connecting the cylinder and the 45 chamber and affording communication between the cylinder, the chamber and the exhaust connection, the said chamber being slidably mounted on the lower end of the said tubular connection, and the said connection having a movement in excess of the 50 said chamber, whereby communication is established between the interior of the chamber and the exhaust connection after the chamber has engaged with the container support.

9. In a machine for vacuum sealing, a container support, a tubular member vertically disposed above the container support and having an air passage in its lower end, 60 an exhaust connection to the tubular member, means for vertically reciprocating the tubular member, a vacuum chamber having an open lower end adapted to be seated on and closed by the said support and having 65 its upper end slidably sleeved on the lower

end of the tubular member, the said tubular member having a downward movement in excess of that required to seat the said chamber on the said support, whereby the air passage in the tubular member is uncovered and 70 communication established between the interior of the chamber and the exhaust connection through the tubular member after the chamber has been seated on the container support. 75

10. In a machine for vacuum sealing, a container support, a tubular member vertically disposed above the support and having an air-passage in its lower end, an exhaust connection to the tubular member, a vacuum chamber slidably mounted on the lower end of the tubular member and having an open lower end, and means for causing relative vertical motion between the said support and the said chamber and tubular member whereby the chamber engages the support and is closed thereby and the chamber is pushed upwardly on the tubular member thereby uncovering the air passage in the lower end of the tubular member and establishing communication between the exhaust connection and the interior of the chamber. 80 85

11. A sealing machine of the class described having, in combination, a support 90 for a receptacle, a vacuum bell adapted when moved into engagement with said support to cooperate therewith to enclose the receptacle, said vacuum bell having an aperture vertically arranged in the wall thereof, a 95 plunger extending through said aperture in the bell, a sealing device arranged within the bell, means for reciprocating said plunger, a connection between the sealing device and plunger for moving the sealing device toward and from said support, a suitable friction slip connection between the bell and said plunger for causing the bell to move with the plunger toward said support until the bell engages said support, then permitting the plunger to move with relation to said bell to move the sealing device further toward said support, causing the bell to move with the plunger during the first part 100 of the retracting movement of the plunger from said support but permitting the retracting movement of the bell to be arrested prior to the completion of the retracting movement of said plunger, and means for thus arresting the retracting movement of 105 the bell. 110 115

12. In a machine for vacuum sealing, a container support, a vacuum-chamber having an open lower end adapted to engage with the container support and be closed thereby, a cylinder above the chamber, a piston in the cylinder adapted to be reciprocated by air pressure, a connection from the piston to the chamber, and a sealing device secured to the lower end of the said connec- 120 125 130

tion, the said chamber being slidably mounted on the lower end of the said connection, and the said connection having a movement in excess of the movement of the chamber whereby the sealing device is given actuating motion after the chamber is engaged with the container support.

13. In a machine for vacuum sealing, an upright column, a carrier revolvably mounted on the column, a stationary valve seated in the upper end of the carrier, a plurality of vertically reciprocating vacuum chambers supported by the carrier, a cylinder above each chamber, a piston in each cylinder actuated by the alternate exhaustion of air from each side of the piston and the alternate admission of air under atmospheric pressure to the opposite side of the piston, and connections leading from the upper end of the carrier adjacent the said valve to the cylinder on either side of the piston, the said valve having a pair of parallel horizontal ports adapted to keep the lower pipe in communication with the exhaust and the upper pipe in communication with the atmosphere during a part of the revolution of the carrier and another pair of parallel horizontal ports adapted to keep the upper pipe in communication with the exhaust and the lower pipe in communication with the air during the remainder of the revolution of the said carrier.

14. In a machine for vacuum sealing, an upright column, a carrier revolvably mounted on the column, a stationary valve seated in the upper end of the carrier, a plurality of vertically reciprocating vacuum chambers supported by the carrier, a cylinder above each chamber, a piston in each cylinder actuated by the alternate exhaustion of air from each side of the piston and the alternate admission of air under atmospheric pressure to the opposite side of the piston, and connections leading from the upper end of the carrier adjacent the said valve to the cylinder on either side of the piston, the said valve having suitable ports adapted to keep the lower pipe in communication with the exhaust and the upper pipe in communication with the atmosphere during a part of the revolution of the carrier and other suitable ports adapted to keep the upper pipe in communication with the exhaust and the lower pipe in communication with the air during the remainder of the revolution of the said carrier.

15. In a sealing machine, a container support, a vacuum chamber having an open lower end positioned above the said support and adapted to engage therewith, a cylinder above the said chamber, a piston in the cylinder, a connecting member between the piston and the vacuum chamber, and means for exhausting the air above and below the piston alternately for the purpose of moving

the said vacuum chamber into and out of engagement with the said support.

16. In a sealing machine, the combination with a continuously rotating package table and a plurality of continuously rotating vacuum chambers having open lower ends adapted to engage with the said table, of means actuated by atmospheric pressure for moving the said chambers into and out of engagement with the said table. 70

17. In a sealing machine, the combination with a plurality of continuously rotating container supports and a plurality of continuously rotating vacuum chambers adapted to engage with and be closed by the said supports, of means actuated by atmospheric pressure for moving the said chambers into and out of engagement with the said supports, and a valve controlling the exhaustion of air from the said actuated means, the said means being brought into and out of communication with the said valve by the rotary motion of the machine. 80

18. A sealing machine of the class described having, in combination, a rotatable carrier, means for rotating the carrier, a plurality of receptacle supports carried by the carrier, a plurality of vacuum chambers carried by the carrier having open lower ends adapted to engage with said supports, respectively, and means actuated by atmospheric pressure for relatively moving said supports and said chambers into and out of engagement in a predetermined timed relation during each complete revolution of said carrier. 90

19. A sealing machine of the class described having, in combination, a support for a receptacle, a vacuum bell adapted when moved into engagement with said support to cooperate therewith to enclose the receptacle, a sealing device located within said bell, means for moving said bell and sealing device toward and from said support, comprising a reciprocating plunger acting during its movement in one direction to move said bell into engagement with said support and during the continued movement of the plunger in said direction to move said sealing device into engagement with the closure of said receptacle, air exhausting means, and means rendered effective by said plunger during said continued movement thereof to open communication between the interior of said bell and said air exhausting means. 105

20. A sealing machine of the class described having, in combination, a support for a receptacle, a vacuum bell adapted when in engagement with said support to cooperate therewith to enclose the receptacle, means for relatively moving said bell and support into engagement comprising a cylinder, a piston within the cylinder, air exhausting means, means for opening communication between the cylinder at one side 110

- of the piston and said air exhausting means, and for admitting air to the cylinder at the other side of the piston, and means acting automatically while said support and bell 5 are in engagement for opening communication between the interior of said bell and said air exhausting means.
21. A sealing machine of the class described having, in combination, a rotatable carrier, means for rotating the carrier, a plurality of receptacle supports carried by the carrier, a vacuum bell and a sealing device associated with each of said receptacle supports, pneumatically operated means for 10 moving each of said vacuum bells into engagement with its associated support and the associated sealing device into engagement with the closure of the receptacle, and means acting automatically to control said 15 pneumatically operated means to thus operate all of said vacuum bells and sealing devices in a predetermined timed relation during each complete revolution of said carrier.
22. A sealing machine of the class described having, in combination, a rotatable carrier, means for rotating the carrier, a plurality of receptacle supports carried by the carrier, a sealing device associated with each of said receptacle supports, pneumati- 20 25 30 35 40 45 50 55
- cally operated means for moving each of said sealing devices toward and from its associated receptacle support comprising a cylinder, a piston in the cylinder, and suitable connection between the piston and said sealing device, air exhausting means, air supplying means, and means acting automatically to open and close communication between each of said cylinders at opposite sides of its piston and said air exhausting and supplying means, respectively, to operate all of said sealing devices in a predetermined timed relation during each complete revolution of said carrier.
23. A sealing machine of the class described having, in combination, a rotatable carrier, means for rotating the carrier, a plurality of receptacle supports carried by the carrier, a sealing device associated with each of said receptacle supports, pneumatically operated means for relatively moving each of said supports and its associated sealing device toward and from each other, and means acting automatically to control said pneumatically operated means to thus operate all of said supports and sealing devices in a predetermined timed relation during each complete revolution of said carrier.

HARRY E. TOWNSEND.
